UNITED STATES PATENT OFFICE.

GEORGE G. FEIGL AND ALEXANDER R. GROSSMAN, OF NEW YORK, N. Y., ASSIGNEES
TO INTERNATIONAL AUTOMATIC MACHINE COMPANY, OF NEW YORK, N. Y., A COR-
PORATION OF NEW YORK.

COIN-CONTROLLED VENDING-MACHINE.

1,053,950.

Specification of Letters Patent. Patented Feb. 18, 1913.

Application filed January 27, 1912. Serial No. 673,957.

To all whom it may concern:

Be it known that we, GEORGE G. FEIGL and ALEXANDER R. GROSSMAN, of the city, county, and State of New York, have invented new and useful Improvements in Coin-Controlled Vending-Machines, of which the following is a specification.

This invention relates to coin controlled vending apparatus of that class in which several articles of merchandise, such as gum, chocolate and the like, may be independently vended in the same machine by the depositing of a coin and the operation of a single lever or the like, and it is the primary object of the invention to provide an apparatus of this character which is cheap and compact in construction, reliable in operation, and particularly adapted to be secured to the backs of opera chairs or other places to take up a minimum amount of space.

It is the principal object of the invention to provide a vending apparatus in which a deposited coin is utilized to actuate the mechanism to eject an article from the apparatus, the coin being released after the ejection of an article and the apparatus is inoperative until another coin is deposited.

Further objects of the invention relate to the construction of the casing whereby ready access may be had to the interior thereof for the purpose of emptying or refilling it, or to get at the operating mechanism; to means to close the said coin chute to prevent the insertion of a coin after all of the articles have been vended; and to means to prevent the return of the coin and thereby the unloading of the machine by a single coin.

In the drawings accompanying and forming a part of this specification, Figure 1 is a perspective view of our improved vending apparatus, partly broken away to illustrate the interior thereof. Fig. 2 is a sectional side elevation, a coin having been deposited and an article about to be ejected. Fig. 3 is a sectional front elevation of the lower portion of the casing and the ejector mechanism taken substantially on the line A—A of Fig. 2. Fig. 4 is a sectional plan view of a portion of the casing to illustrate the means to close the coin slot. Fig. 5 is a sectional side elevation of the

lower portion of the casing, a coin having been deposited and the mechanism about to be operated to eject an article. Fig. 6 is a view similar to Fig. 5, but showing the mechanism in the position it assumes when an article is being ejected. Fig. 7 is a perspective view of the coin slot closing means; and Fig. 8 is a perspective view, partly in section, of the actuating shaft.

Similar characters of reference designate like parts throughout the different views of the drawings.

As a preface to a detailed description of the construction and operation we wish to state that in the present instance the invention is illustrated in connection with an apparatus comprising three package containers and three sets of ejector mechanism, either one of which may be connected to the operating shaft by the depositing of a coin in the coin chute, or all three may be simultaneously connected to the operating shaft by the depositing of a coin in the coin chute for each package container, although it will be obvious that a greater or less number of package containers may be employed.

In the embodiment of the invention illustrated in the drawings the packages and mechanism are inclosed in a casing comprising a back 9 secured by screws to a frame constituting the sides and bottom, a cover or front wall 11 pivotally supported at the bottom by the sides, as at 12, and at the top by a rod 13 passing through lugs on the cover and engaging in the sides, the said rod retained in position by a key actuated lock 14 the bolt of which has a cut out portion to engage in an annular recess in said rod. A plate 15 also extends across the front, and is fulcrumed on the edge of an upwardly projecting flange of the bottom with its upper end bearing against lugs 16 and retained in position by flanges 17 on the cover bearing against the same. The plate 15 also serves as a deflector for an ejected package and is provided with a lip 18 to constitute a receptacle or receiver for the ejected package.

The package containers for a superposed pile of packages (designated in a general way by P.) consist of a back 19, one of the side walls 20 and ledges 21 upon which the packages are supported constructed or cast integral with the frame 10, the front of the

containers being open and the packages retained therein by the cover 11. The other side wall of the containers comprise a member 22 (Fig. 7) having nibs at 23 at the top and bottom whereby they are pivotally supported in lugs 24 on the frame 10 at the top and the ledges 21. The upper end of the member 22 is bent, as at 25, for a purpose to be hereinafter described. The back 10 of the containers are also provided with channels 26 which with the back 9 constitute a continuation of coin chutes 27 formed in a connecting rib 28 of the sides of the frame 10.

15 The arms 25 of the container sides 22 are adapted to engage in the coin chutes and prevent the insertion of a coin after all of the packages have been ejected, and for this purpose they are provided with springs 29 bearing against the sides and tending to swing the members 22 on their pivots toward the packages. The members 22 are cut away at the bottom, as at 30, (Fig. 7,) to clear a follower weight 31 when all of 25 the packages have been ejected and said weight rests upon the ledges 21.

30 The ejector mechanism comprises a shaft 32 journaled in the sides of the frame 10 with the ends projecting out therefrom with knobs 33 fixed to said ends. The shaft is provided with slots 34, (Fig. 8,) one located below each package container and in line with a coin chute. The movement of the shaft is limited by a pin 37 in one of 35 the knobs engaging in a slot 38. Ejectors 35 are rotatably mounted on a fixed shaft 36, the said ejectors constructed of sheet metal and bent to form continuations of the coin chutes 27 when in normal position, as 40 shown in Figs. 2 and 5.

45 When a coin 39 is deposited it passes through the coin chute into a slot in the actuating shaft 32 and rests upon a seat or abutment 40 fixed on the shaft 36. Figs. 2 and 5. As the shaft 32 is rocked the coin engages with and rocks the ejector forward, an upwardly projecting portion 41 thereof, which normally engages in back of the lowermost package of the pile, and 50 also serves as a guide for the coin, pushes the lowermost package from beneath the pile, the forward edge of the package pushing up a spring 42, which then bears down on the package, and as a full forward movement is imparted to the shaft 32 causes the package to fall upon the deflector plate 15, as shown in Fig. 6, when it is caught by the lip 18. As the ejector approaches the limit of its forward movement the top edge of 55 the coin rides along a cam edge 42 on the ejector slightly pushing the coin downward, as shown in dotted lines in Fig. 6, and as the shaft 32 and ejector are returned to normal positions by their springs 43, 44, 60 the coin will abut against its seat 34, thus

locking the shaft against return movement and preventing the unloading of the apparatus by the depositing of a single coin, and permitting the coin to drop by gravity through the slot in the shaft into the bottom of the casing. The spring 42 also serves to prevent the fraudulent removal of the packages, as by a hat pin or the like, as should any attempt be made to pry the package forward it will abut against said 75 spring.

Variations may be resorted to within the scope of our invention.

Having thus described our invention, we claim:

1. In a vending machine, the combination with a casing provided with a support for a pile of packages, of a coin slot in the top of the casing; a coin chute extending down from said slot in back of the package support; a pivotally supported ejector arm normally in position with its free end in back of the lowermost package of the pile; a rock shaft journaled in the casing below the coin chute in the rear of the ejector arm and having a slot extending transversely therethrough, said slot when the shaft is in normal position being in line with the coin chute, and adapted to receive a coin deposited in the coin chute; means to support the coin when engaging in the shaft slot and the shaft is in normal position with the upper edge of the coin projecting therefrom, said projecting edge as the shaft is rocked engaging with and rocking the ejector arm forward thereby ejecting the lowermost package of the pile, and the coin as the ejector arm is rocked forward being thrown out of engagement with its support and forced through the shaft slot. 105

2. In a vending machine, the combination with a casing provided with a support for a pile of packages, of a coin slot in the top of the casing; a coin chute extending down from said slot in back of the package support, a pivotally supported ejector arm; a spring to normally maintain said arm in position with its free end engaging in back of the lowermost package of the pile; a rock shaft journaled in the casing below the coin chute in the rear of the ejector arm and having a slot extending transversely through the same, said slot when the shaft is in normal position being in line with the coin chute and adapted to receive a coin deposited in the coin chute; a fixed support upon which the coin rests when engaging in the coin slot and the shaft is in normal position with the upper edge of the coin projecting therefrom, said projecting edge of the coin as the shaft is rocked engaging with and rocking the ejector arm forward ejecting the lowermost package from the pile, and said coin being thrown out of engagement with its support as the shaft is 130

rocked forward and thereby permitted to drop through the shaft slot.

3. In a vending machine, the combination with a casing for a pile of packages, of a coin slot in the top of the casing, a coin chute extending down from said slot in back of the package support; a pivotally supported ejector arm normally in position with its free end engaging in back of the 10 lowermost package of the pile, said ejector arm being provided with a cam portion; a rock shaft journaled in the casing below the coin chute in the rear of the ejector arm and having a slot extending transversely 15 therethrough, said slot when the shaft is in normal position being in line with the coin chute and adapted to receive a coin deposited in the coin chute; a fixed seat arranged under the transverse slot with its 20 upper edge projecting therefrom when the shaft is in normal position, said projecting portion of the coin as the shaft is rocked engaging with and rocking the ejector arm forward, the said coin as the shaft is rocked 25 also being swung from its seat and brought in engagement with the cam portion of the ejector arm which forces the coin through the shaft slot.

4. In a vending machine, the combination 30 with a casing provided with a support for a pile of packages, of a coin slot in the top of the casing; a coin chute extending down from said slot in back of the package support; a pivotally supported ejector arm 35 normally in position with its free end engaging in back of the lowermost package of the pile, said arm formed with a chute constituting a continuation of the chute in the casing when the arm is in normal position; a rock shaft journaled in the casing 40 below the coin chute in the rear of the ejector arm and having a slot extending transversely therethrough, said slot when said arm and shaft are in normal position 45 being in line with the arm chute; a fixed seat arranged under the slot in the rock

shaft to support a coin within the slot with its upper edge projecting therefrom when the shaft is in normal position, said projecting portion of the coin as the shaft is rocked 50 engaging with and rocking the arm forward; and the coin simultaneously therewith being swung away from its seat so as to permit it to drop through the shaft slot.

55

5. In a vending machine, the combination of a casing provided with a support for a pile of packages, of a coin slot in the top of the casing; a coin chute extending down from said slot in back of the package support; a fixed rod extending below the package support; an ejector arm pivotally mounted on said rod with its free end normally engaging in back of the lowermost package of the pile and formed with a 60 chute normally in register with the coin chute to constitute a continuation of the latter; a rock shaft journaled in the casing below the coin chute in the rear of the ejector arm and having a slot extending 65 transversely therethrough, said slot when said arm and shaft are in normal position being in line with the coin chute in the arm and in which a deposited coin is adapted to engage; and a fixed seat upon the rod to 70 support the coin within the shaft slot with its upper edge projecting therefrom when the shaft is in normal position, said projecting edge of the coin as the shaft is rocked 75 engaging with and rocking the ejector arm forward and simultaneously with the rocking of the arm thrown away from its seat to permit it to drop through the shaft slot.
